ART OF UPHOLSTERING AND WEB AND
SPRING ASSEMBLY THEREFOR

Mac Levine, Brooklyn, N. Y.

Application February 18, 1939, Serial No. 257,205

5 Claims. (Cl. 155—179)

This invention relates to the art of upholstering and to a web and spring assembly such as is useful for upholstering purpose, for instance, for upholstering the seats and backs of chairs, couches, automobiles, bed bottoms, and other structures or items of furniture into which coil springs usually enter so as to afford a resilient foundation against and on which the body may be comfortably posed or supported. It deals more especially with a prefabricated web and spring assembly such as reaches the furniture-maker or user ready for installation in the item of furniture or frame to be upholstered.

The web or webbing forming part of the assembly of the present invention may consist of a band of stout, woven fabric, for instance, jute-yarn fabric, such as has heretofore been used for staying coil springs in upholstered furniture. The usual prior art practice involves, however, the initial step of fastening web lengths to the frame and then sewing the end turns of the coil springs to the already-fastened lengths. The assembly hereof, on the other hand, is prefabricated in the sense that the coil springs ultimately to be stayed by the web in the finished article of furniture or other upholstered structure are preliminarily mounted and stayed in the desired spaced relationship on the web, wherefore, the assembly may then be fastened with minimum effort to the article of furniture or other structure to be upholstered even by comparatively unskilled workmen. By virtue of its being prefabricated as a distinct entity or article of manufacture apart from the article of furniture or structure to be upholstered thereby, the assembly hereof can readily and economically be fabricated with more effective and longer-enduring elements for staying or fastening the springs to the web in the predetermined or spaced relationship desired. Thus, it becomes possible according to the present invention to stay the springs on the web by metallic fastener elements, such as pronged rivets, staples, clips, or their equivalents, which may be anchored firmly to the web fabric and then be clinched tightly over the desired regions of an end turn of each coil spring so that the spring cannot be dislodged excepting in the remote and unlikely contingency that the stout web fabric itself is ruptured or otherwise gives way at the region of anchorage of the metallic fastener thereto.

Another advantage of the present invention is that it enables the manufacturer of the assembly hereof to supply the user with such assembly in the form of an indefinite or continuous length,

for instance, as a roll accumulation or as a folded package. So that the assembly hereof may be stored and shipped while occupying a small compass and hence affording important economy, the present invention preferably also involves compressing or substantially flattening the springs in the assembly and maintaining the springs in compressed or substantially flattened state until the assembly has been fastened in desired position to the frame in which it is to serve its ultimate use. While various expedients may be adopted in maintaining the springs of the assembly hereof in compressed or flattened state, a desirable one is to secure to the web immediately under the end turn of each spring a fabric strip whose end portions are free and can be brought together in lapping relationship over the free end turn of the spring while in compressed or substantially flattened state and then be fixed in such lapping relationship, as by an eyelet, rivet, staple, or the like, to the web fabric, thereby tightly encompassing the spring in its substantially flattened state and maintaining it in such state. With the springs thus assembled in substantially flattened state with the web to which they are stayed, not only does it become possible conveniently to put up the assembly as a roll accumulation or as a folded package occupying comparatively little space, but the work of installing the assembly is facilitated, since the springs do not interfere with the operators as they proceed to cut desired lengths of the assembly from an accumulation, or stretch the lengths taut on the frame to be upholstered, or fasten the lengths in taut condition to the frame. Moreover, there is no tendency whatever for the compressed or substantially flattened springs of the assembly to entangle or interlock with one another during shipment, either when the assembly is pre-cut as predetermined lengths or exists in the form of a continuous length or accumulation; and the user is hence not put to the trouble and expense of disentangling the springs from one another. Once the assembly hereof has been installed or tacked in place for ultimate service, it is a simple matter to restore the springs to their normal height, for, by merely cutting or snipping transversely the spring-confining strip along two transverse lines each lying outside of the fastener for the overlapping strip portions, the springs are released or permitted to recoil to their normal height.

With the foregoing and other features and objects in view, the present invention will now be described in further detail with particular reference to the accompanying drawings, wherein,

Figure 1 depicts in perspective a coil spring and a fragment of web carrying a spring-confining strip thereon and prepared or conditioned, pursuant to the present invention, for the retention of an end turn of such spring in producing a fragment of the assembly hereof.

Figure 2 is a composite front-elevational and longitudinal or medial sectional view of a fragment of the assembly produced from the elements appearing in Figure 1, the web, spring-confining strip, and the lower end turn of the spring being shown in section and the lower end turn being fastened at one region to the web.

Figure 3 is a fragmentary plan view of the assembly hereof at a region where the end turn of a spring has been clinched by a metallic fastener to the web, such fastener serving also to unite the spring-confining fabric strip to the web.

Figure 4 represents a longitudinal or medial section through a fragment of the assembly with the spring in compressed or substantially flattened state and with the end portions of the spring-confining strip brought upwardly over the sides of the spring toward each other and meeting in lapping relationship substantially at the center of the concentric spring turns.

Figure 5 is a view similar to Figure 4, excepting that it shows an eyelet driven through the lapping end portions of the spring-confining strip and through the web, the spring thus being maintained in substantially flattened state.

Figure 6 shows in perspective an indefinite or continuous length of the assembly hereof convoluted into roll form.

Figure 7 similarly shows an indefinite or continuous length of the finished assembly hereof folded to and fro into stack form.

Figure 8 illustrates in perspective the assembly hereof installed in the back of a chair, some of the springs appearing in compressed or substantially flattened state and others in released or normal state.

Figure 9 shows in perspective a fragment or length of a modified form of assembly embodying the invention hereof, such form being especially adapted for heavy duty, as in a chair seat.

Figure 10 illustrates in perspective the assembly of Figure 9 installed in a chair seat, the padding and external fabric of which is shown broken away.

As indicated in Figure 1, the web used for the purposes hereof may consist of a band 10 of stout, woven fabric, such as jute-yarn fabric or its equivalent, which band may be of a width ranging from about $2\frac{1}{2}$ to about $4\frac{1}{2}$ inches. Superposed on the web or band 10 is a narrower strip 11, which is designed to serve as the element for confining or holding a spring in compressed or substantially flattened state. The strip 11, which may consist of canvas or other relatively inexpensive fabric and may be of a width considerably less than that of an end turn of the spring to be confined thereby, is preferably positioned so that its longitudinal medial line substantially coincides with that of the web 10. The metallic fastener or fasteners for fixing an end turn of a coil spring to the web 10 may be of any suitable type. The pair of fasteners shown for such purpose in Figure 1 are so-called double-prong rivets, the prongs 12 of which may be readily forced or driven through the fabric of the web 10 and the fabric of the strip 11 the heads 13 of which are of substantial area and hence engage against sufficient web fabric to be

strongly resistant against being pulled through such fabric. The pair of rivets may lie substantially on the longitudinal medial line of the web 10 and the strip 11 and be spaced from each other a distance corresponding substantially to the diameter of an end turn of the coil spring to be stayed on the web.

It should be appreciated that in actual practice a pair of the pronged rivets may in appropriately spaced relationship be driven in a single operation through a continuous web or band, a strip 11 being superposed on the web at each of the spaced areas thereof on which it is to be prepared for assembly with a coil spring, as already described.

After a web portion has been prepared for assembly with a coil spring, for instance, the usual double-cone or hour-glass coil spring 14 appearing in Figure 1, an end turn 14a of such spring may be placed on the prepared web portion so that diametrically opposite regions of such end turn are received within the spaces 15 defined between the prongs 12 of each rivet. It will be noted that the web 10 is of a width approximating the diameter of an end turn 14a of each coil spring. The prongs, which are preferably offset slightly relative to each other and are vertically upstanding from the edge or peripheral portion of the rivet head 13, may then be clinched or bent by a suitable clinching tool toward each other over the round wire constituting the end turn 14a, as best shown in Figures 2 and 3. The desired tenacious fixation of the end turn 14a to the web 10 is ensured by providing prongs 12 of a length sufficient to engage over a substantial arcuate portion of the wire of such end turn, for instance, an arcuate portion ranging from about 90° to 180° . When its prongs are clinched over the end turn 14a of the spring, the rivets also function to unite the strip 11 firmly to the web 10. It might be noted that fixation of a coil spring to the web 10 may be performed on a continuous web as it is being withdrawn from a roll, successive portions of such web each being acted upon by a machine adapted to drive a pair of pronged rivets or staples there-through and through a spring-confining strip 11, receiving the end turn of a coil spring within the spaces defined by the prongs of each of the pair of rivets, and then being acted upon by a suitable tool serving to clinch the prongs over the end turn of the spring and thereby to effect such fixation. In some instances, however, the pronged rivets may in essentially one operation be driven through the web 10 and the strip 11 and their prongs immediately clinched in position over the end turn of a spring appropriately positioned on the strip during the rivet-driving operation, in which latter case a web may be fed from a roll through the rivet-driving machine as the operator mounts successive spring-confining strips and springs in the desired spaced positions on the web for fixation to the web. As the web and spring assembly hereof emerges from the rivet-driving and/or rivet-clinching instrumentality, predetermined lengths may be cut from the continuous assembly; or, if desired, the continuous assembly may be maintained as such for the spring-compressing or spring-flattening operation presently to be described.

Each spring of the assembly hereof may, as shown in Figure 4, be compressed until its height is only a small fraction of its normal or original height. Thus, an hour-glass spring having a normal height of, say, about 8 to 10 inches, may

be compressed until reduced to a height of, say, about one-half inch or even less. Such compression may be accomplished in any suitable way, for instance, in a spring-compressing jig capable of exerting pressure on opposite spring sectors lying outside of that sector to be engaged or encompassed by the end portions of the spring-confining strip 11. While the spring 14 is in compressed or substantially flattened state, the free end portions 11a of the strip 11 are brought upwardly over the spring toward each other and brought together tightly in lapping relationship at substantially the center or axis of the concentric spring convolutions. Thereupon, as indicated in Figure 5, an eyelet 16 or its equivalent may be driven through the lapping portions of the strip 11 and through the superposed strip and web layers 11 and 10, respectively, in consequence of which the spring is confined or held in its compressed state. With the successive springs of the continuous assembly hereof confined or maintained in such compressed state, it is possible to convolute the continuous assembly into a roll R, such as depicted in Figure 6, or into a zig-zag folded stack or package P, such as shown in Figure 7, or into some other compact and convenient accumulation or package. In some instances, on the other hand, the continuous assembly hereof comprising springs in compressed or substantially flattened condition may be cut into lengths predetermined to suit the ultimate user's purpose.

At its place of use, for instance, in an establishment for manufacturing chairs equipped with upholstered backs and/or seats, the continuous web and spring assembly hereof may be cut into the desired predetermined lengths, if this has not already been done by the assembly manufacturer. A chair back upholstered with the assembly hereof is illustrated in Figure 8, wherein a chair frame F of wood or the like is shown as comprising a rectangular or box-like back frame B defined by upper and lower back frame members 17 and 18, respectively, and side members 19. Extending vertically from the upper back member 17 to the lower back member 18 are shown a plurality of lengths of the web and spring assembly hereof, which lengths may be tacked in taut condition at their marginal portions to such members. Because the springs assembled with such lengths as they are being installed are in compressed or substantially flattened state, the upholsterer encounters no trouble whatever in stretching such lengths to a taut condition as he tacks or fastens them at their marginal portions to the upper and lower back members. After installation in the back, the springs of the assembly may be released or permitted to recoil to their normal height; and, to this end, each of the spring-confining strips 11 is cut, as with a knife or scissors, along transverse lines on each side of the eyelet 16 or like fastener. The strip pieces thus created in the course of releasing a spring comprise a piece 11b lying immediately next to the web 10 and immediately under the end turn of the spring anchored to the web, such piece preferably extending somewhat beyond the pronged rivet fasteners and thus serving to reinforce the web, whereat there is especial tendency for wear, namely, immediately under the end turn 14a. Such pieces 11c as correspond to the previously lapping end portions of the strip 11 and/or as lie within the end turn 14a may either be left as such or be trimmed away close to the eyelet 16 or its equivalent.

Since the web portions at the central zones of the successive lengths of the web and spring assembly hereof, as installed in a chair back, usually undergo maximum deflection in use, it is desirable to inhibit excessive stretching tendency at such portions. As shown in Figure 8, undue or excessive stretching at such web portions is obviated by reinforcing such portions with a transversely extending web 20 tacked or fastened in taut condition to the side members 19 of the back and suitably interlaced with the vertically extending webs 10. Highly effective interlacing of the transversely extending web 20 may be realized when, as shown, the end convolution 14a of each spring 14 is of a diameter greater than the width of a spring-staying web 10, for, in such case, the web 20 may be inserted or threaded through an opening 21 corresponding to a sector defined by one edge of the spring-staying web 10 and an end turn 14a, thence under the back face of the web 10, and thence out through another opening 21a corresponding to another sector defined by the opposite edge of the spring-staying web 10 and the end turn 14a, such threading being repeated through the similar, transversely aligned openings 21 and 21a associated with the successive vertical lengths of the assembly hereof. Of course, reinforcing transverse lengths of web 20 may also be used for reinforcing the other transversely aligned web portions lying immediately in back of the springs, at which deflecting pressure or stress is exerted on the spring-staying webs. Again, the web and spring assembly lengths hereof may be installed so as to extend transversely across the chair back, in which event the reinforcing webs would be interlaced with the assembly lengths vertically of the frame, that is, would extend in criss-crossing relationship to the assembly lengths. When the installation of the web and spring assembly hereof in a chair back has been completed, the usual subsequent upholstering steps may be performed, including the tying or lashing of the free end portions of the released springs to the frame B, the covering of the upper spring portions with felt or padding, and the covering of the padding with the desired external or exposed upholstery fabric.

While the web and spring assembly hereinbefore described may be installed in chair seats or bottoms, yet a more advantageous form of assembly hereof for use in a chair seat is shown in Figure 9, wherein there appears, in addition to the main spring-staying web 10, an auxiliary or supplementary spring-staying web 22. The web 22 may be of fabric similar to that of the web 10; and, although depicted as being distinctly narrower than the web 10, it may be as wide or even wider than the web 10, if desired. The web 22, like the spring-confining strip 11, may be fastened to the strip 10 by the very same pronged rivets or equivalent fasteners as serve to fix an end convolution 14a of the spring 14 to the web 10. A length of the web and spring assembly of Figure 9 is depicted in Figure 10 as being installed in a chair seat or bottom, whose rectangular or box-like frame is of substantial height or depth and comprises back and front rails or frame members 23 and 24, respectively, and side rails or frame members 25.

An important advantage of the form of assembly of Figure 9 is that it comprises web lengths adapted for securement at both the upper and lower edges or faces of the seat frame, for, as appears in Figure 10, the free end por-

tions 26 of the web 10 may be tacked or otherwise suitably fastened in taut condition to the lower edges of the rails 23 and 24, whereas the free end portions 27 of the auxiliary web 22 may be tacked or otherwise suitably fastened in taut condition to the upper edges of such rails. In effect, therefore, one realizes thereby the suspension or auxiliary support afforded by the auxiliary web 22 as well as the primary support afforded by the web 10. As in the chair back of Figure 8, the lengths of web and spring assembly hereof installed in the chair seat of Figure 10 may be reinforced by web lengths 28 tacked or otherwise suitably fastened in taut condition at their end portions to the lower edges of the rails 25 and interlaced in criss-crossing relationship with the already-installed lengths of the web and spring assembly hereof. One or more such reinforcing web lengths 28 may be used to reinforce the installed lengths of web and spring assembly hereof. It is especially desirable thus to reinforce the installed assembly lengths at their aligned central spring-supporting portions, at which maximum deflection tends to occur. It will, of course, be understood that in installing the form of web and spring assembly shown in Figure 9 in a chair seat or bottom, the springs are released from their compressed or substantially flattened state, as has already been described; and the fabric pieces 11b and 11c into which the original spring confining strip 11 is cut so as to release the springs may serve the same function and/or be treated in the same manner as has already been described in connection with the similar pieces of Figure 8. The upper or free end portions of the springs 14 of Figure 10 may be tied or lashed, as customarily, to the upper edges of the frame rails 23, 24, and 25, whereupon the upholsterer may proceed to cover the upper spring portions with a layer of felt or padding 29 of suitable thickness and to cover such felt or padding with the desired external or exposed upholstery fabric, such as cloth, leather, etc.

A web and spring assembly embodying the invention hereof may depart in one or more respects from the particular exemplary assemblies hereinbefore described. Thus, in lieu of using a separate spring-confining strip for each of the springs, it is possible to use one strip for the purpose of confining a plurality or succession of springs in a compressed or substantially flattened state. In such instance, it is necessary to provide free end strip portions of sufficient length to be folded over the desired number or succession of springs and to be tied together in lapping relationship at substantially the central region of at least one of the compressed springs, an eyelet, rivet, or like fastener being driven through such lapping portions and through the spring-staying web and also through the strip and the spring-staying web at substantially the center of each of the other springs to be confined in a substantially flattened state. Again, it is possible to use suitably stout strand material, such as rope, for encompassing or confining each substantially flattened spring or a succession of such springs, in which case, a fastener element or fastener elements separate from those serving to stay the end turn of a spring may be necessary to anchor the spring-confining strand material to the spring-staying web. The spring and web assembly hereof is not necessarily limited to the

use of stout, woven fabric as the spring-staying web material, for such spring-staying web material may be replaced by suitably flexible metallic bands or webs. Other changes or modifications are possible in the web and spring assembly hereof without departing from the spirit or scope of the invention hereof as defined by the appended claims.

The expression "coil-spring" is used in the foregoing description and in the appended claims in its comprehensive sense to denote various forms or shapes of upholstering springs, for instance, cylindrical and conical forms of springs as well as a double-conical or hour-glass form of spring.

I claim:

1. A prefabricated assembly for upholstering purpose comprising a web, coil springs mounted in spaced relationship and in substantially flattened state on said web, means for staying said springs on said web, and readily severable strip material tightly encompassing and maintaining said springs in substantially flattened state on said web.

2. A prefabricated assembly for upholstering purpose comprising a web, coil springs mounted in spaced relationship and in substantially flattened state on said web, fasteners for staying said springs on said web, and readily severable strip material united to said web by said fasteners, said strip material tightly encompassing and maintaining said springs in substantially flattened state on said web.

3. A prefabricated assembly for upholstering purpose comprising a web, coil springs mounted in spaced relationship and in substantially flattened state on said web, means for staying said springs on said web, a readily severable strip tightly encompassing and maintaining each of said springs in substantially flattened state on said web, each said strip including a portion underlying each spring and end portions overlying each spring and lapping each other at substantially the center of each spring, and a fastener passing through said lapping strip portions and said web.

4. A prefabricated assembly for upholstering purpose comprising a web, coil springs mounted in spaced relationship and in substantially flattened state on said web, fasteners for staying said springs on said web, a readily severable strip tightly encompassing and maintaining each of said springs in substantially flattened state on said web, each such strip including a portion underlying each spring and united to said web by said fasteners and end portions overlying each spring and lapping each other at substantially the center of each spring, and a fastener passing through said lapping strip portions and said web.

5. In the art of upholstering back and bottom frames with webs and coil springs, those steps which comprise mounting such springs in spaced relationship on a web, staying each spring on the web at the end turn contacting with the web, substantially flattening each spring and confining it in substantially flattened state, installing the resulting web and spring assembly in such frames, and releasing said springs from confinement in substantially flattened state to their normal height.

MAC LEVINE.
